DESIGN FOR A GIFT PACKAGE

Mary H. Lull, New York, N. Y.

Application January 30, 1941, Serial No. 98,530

Term of patent 3½ years

To all whom it may concern:

Be it known that I, Mary H. Lull, a citizen of the United States of America, residing at New York, in the county of New York and State of New York, have invented a new, original, and ornamental Design for a Gift Package, of which the following is a specification, reference being had to the accompanying drawing, forming a part thereof.

Figure 1 is a top plan view of a gift box, showing my design; and

Figure 2 is a side elevational view thereof, one side wall of the box and the flange of the lid being shown broken away.

I claim:

The ornamental design for a gift package, as shown and described.

MARY H. LULL.
